(57) **CLAIM**

The ornamental design for a puzzle device, as shown and described.

DESCRIPTION

FIG. 1 is a top perspective view of a puzzle device incorporating the design of the present invention.

FIG. 2 is a bottom perspective view thereof.

FIG. 3 is a top view thereof.

FIG. 4 is a bottom view thereof.

FIG. 5 is a front side view thereof.

FIG. 6 is a rear side view thereof.

FIG. 7 is a left side view thereof; and,

FIG. 8 is a right side view thereof.

The broken lines show portions of the puzzle device that form no part of the claimed design.
